What is claimed is the ornamental design for a detachable face hitch protector, as shown and described.

DESCRIPTION

FIG. 1 is a perspective view of a detachable face hitch protector, showing the new design;

FIG. 2 is an exploded perspective view thereof, illustrating a detachable face and a hitch protector portion;

FIG. 3 is a front elevational view thereof;

FIG. 4 is a rear elevational view thereof;

FIG. 5 is an exploded right-side elevational view thereof;

FIG. 6 is an exploded left-side elevational view thereof;

FIG. 7 is an exploded top plan view thereof;

FIG. 8 is an exploded bottom plan view thereof;

FIG. 9 is a rear elevational view of the detachable face;

FIG. 10 is a front elevational view of the hitch protector portion; and,

FIG. 11 is an alternate perspective view of the hitch protector portion.

The broken line showing of details shown in FIGS. 7 and 8 is included for the purpose of showing environmental portions of the detachable face hitch protector and forms no part of the claimed design.
